[57] **CLAIM**

We claim the ornamental design for a hard hat hanger, as shown and described.

DESCRIPTION

FIG. 1 is an upper left perspective view of a hard hat hanger according to the invention;

FIG. 2 is a lower right perspective view;

FIG. 3 is a left side view, the right side being a mirror image;

FIG. 4 is a section taken on line 4 of FIG. 3 showing the structural form of the invention;

FIG. 5 is a front view;

FIG. 6 is a top view;

FIG. 7 is a bottom view;

FIG. 8 is a back view; and,

FIG. 9 is an environmental perspective view.

The broken line showing of a hard hat in FIG. 9 is for illustrative purposes only, and forms no part of the claimed design.
